WINDING MACHINE

Filed Sept. 9, 1927

Fig. 2.

INVENTOR.
GEORGE F. ECKSTEIN.
BY *W. L. Dempsey*,
ATTORNEY.

UNITED STATES PATENT OFFICE

GEORGE F. ECKSTEIN, OF BUFFALO, NEW YORK

WINDING MACHINE

Application filed September 9, 1927. Serial No. 218,486.

This invention relates to winding machines, and more especially to a winding head adapted to wind flexible strips which have been coated with a viscous substance, and is an improvement upon the winding head disclosed by me in a pending application for patent filed January 21, 1927, and bearing Serial No. 162,564.

The primary object of my invention is to provide a winding head that can be readily adjusted to the varying conditions which arise in winding roofing strips into hollow rolls.

A further object of my invention is to provide a winding head which utilizes a plurality of rotatable rolls in such a manner that the angle at which the material being wound approaches the roll will be such as to make the winding certain and accurate.

Other objects and advantages of my invention will be pointed out in the specification, claim and drawing, in which:

Fig. 1 is a side elevation of a portion of an automatic winding machine showing my improvement.

Fig. 2 is a graphical illustration of the angles at which the material approaches the roll.

Many unsuccessful attempts have been made to construct an automatic winding head capable of winding into hollow rolls strips of flexible material previously coated with a viscous substance. Especially is this true of roofing material, and until the invention and installation of the machine herein described all roofing has been wound by hand.

In the manufacture of various grades of roofing material, thin broad sheets of paper, or other fibrous material are drawn through hot liquid or semi-liquid asphalt, coal tar, or other suitable coating. While still hot and viscous the surface is covered with a coat of finely ground stone, slate, or other suitable material. The coated sheets are then passed over a large series of horizontally dis-

posed rolls so that the sheets hang down between the rollers in festoons, to permit of more rapid drying. It is, therefore, evident that under the most careful and efficient way of handling and coating the material, the thickness of the sheet necessarily varies to a considerable extent, hence it is equally obvious that any winding head for successfully winding material of the class described must be readily adjustable to these varying conditions.

Another factor that makes the winding of roofing material more difficult is that the material is extremely flexible and limber, so that the greatest care is necessary to prevent its doubling back at a sharp angle upon itself for the reason that when it becomes cold and less flexible, attempts to straighten it out will result in breaking and cracking.

For these reasons, it has been found that the angle at which the material approaches the rollers, that is the angle enclosed between tangential lines drawn tangent to each of two rolls towards which the material to be wound is approaching, must not only be as large as possible, but must be capable of being varied to suit the thickness of the material being wound, and also the thickness of the coating, otherwise the winding head crumples the material and prevents the successful winding of the material into a hollow cylindrical body, which is necessary in the roofing art.

Another necessary requisite for a successful roofing winding machine is that the face of the rollers that come in contact with the surface of the material must be perfectly smooth and polished to prevent injury to the material being wound. Should the rollers be notched, indented or grooved, either the sticky coating would adhere to the rolls and build up a rough surface on the rolls, or the indentations and notches would catch on the soft, easily torn roofing and destroy it.

Another condition met with, and which must be overcome, is that should the

viscous coating, or the finely ground second coating be thicker on one edge of the strip than upon the other, as the roll increased in diameter, it would become larger at one end than at the other end, hence the adjustments for one end of the roll must be independent of the adjustments for the other end.

Again, in winding roofing material, it is necessary that a proper pressure be maintained 10 on the roll in order that the material may be wound neither too tightly or too loosely. When winding light thin sheets the pressure of the winding rolls upon the roll of roofing material being formed must, of course, be 15 less than when winding heavier stock.

To meet the conditions and overcome the objections above set forth, I have devised an adjustable winding head capable of being adjusted to different pressures to suit different 20 thicknesses and kinds of material and, also, capable of being independently adjusted at each end of the roll being formed, and also adjustable vertically relative to the material being wound.

25 In Fig. 1, the horizontal dotted line 1 represents a sheet of coated paper passing through the machine described in my pending application above referred to. The dotted line 1 in Fig. 2 illustrates the necessity of properly 30 positioning the winding rolls, which consists of three separate sets. The lower set 2 positioned in a horizontal plane consist of three rolls driven anti-clockwise by means of sprockets and chains, not shown or claimed. 35 Another set of rolls 3 consists of two rolls, also driven anti-clockwise, and adjustably supported upon the movable arm 4. A third set of rolls 5 consists of two rolls driven anti-clockwise and adjustably supported by means 40 of the arm 6.

In Fig. 1 the roll 7 represents the roll being formed. The sheet of roofing passes into the winding head from the feed roller 8, over the two rolls 9 and 10, and strikes the third 45 roll 11 of the set 2, which revolving anti-clockwise directs the end of the roll upwardly until it contacts with the roll 12 of the series 3, which continues to direct the end of the sheet upwardly, and the same condition 50 occurs when the sheet strikes the rolls 13, 14 and 15.

By reference to the graphical illustration in Fig. 2, it will be readily understood that should the rolls be disposed relative to each 55 other in such a manner as to cause the incoming sheet 1 to strike in the apex of an angle, as for instance at 16, instead of the sheet being formed into a roll, it would be caught and crumpled between the rolls. Experience has 60 proven that should the rolls be put in position so that lines 17 and 18 drawn tangent to the rolls 20 and 22 formed an acute angle at 16 instead of an obtuse angle as shown, it would be impossible to form the sheet into a roll, 65 hence I have so designed my winding head

that a line 18 drawn tangent to the roller 20, at the point C and a line 17 drawn tangent to the roller 22 at the point D, form an angle of more than 120 deg. So, also, it is necessary that the angle formed by any two lines drawn tangent to any two companion rolls must be as large as possible to prevent the rolls from crumpling the end of the sheet being wound.

It has, also, been found by experience that the whole winding head must be adjusted with reference to the horizontal line 1, in order to take care of different grades and thicknesses of material being wound. It is, therefore, the method for adjusting the winding head that constitutes the essence of my invention, and it is quite obvious that other means than those indicated in the drawing and herein described could be used for obtaining the adjustments and varying the pressure of the winding rolls upon the roll of material being wound.

In the present invention, the set of rolls 2 are rotatably mounted upon the arm 23 and pivotally held in position partly by means of the link 24 and partly by means of the member 25 slidably movable upon the bracket 26, and held against longitudinal movement by the member 27 between the adjusting screws 28 and 29. It is evident that if the member 25 be moved to the right or to the left, it would change the position of the rolls designated as a whole as 2, and also change the relative position of the arm 6, on which the rolls 14 and 15 are mounted, the arm 6 being pivotally attached to the member 25.

In order to regulate the pressure of the rolls 12 and 13 upon the roll 7 being formed, the arm 4, on which the rolls 12 and 13 are mounted is pivotally supported by the member 32, which is also slidably mounted upon the frame and adjusted by the screws 33 and 34. Since both sides of the machine are identical, the same adjustments can be made at either side of the machine independent of the other side of the machine. In order to vary the pressure of the winding rolls upon the roll being formed, a scale beam 35 is provided adjustably attached to the disc 36, which in turn is pivoted about the point 37. An arm 38 is rigidly attached to the disc 36 at its upper end and pivotally attached to the link 39 at its lower end, the opposite end of the link 39 being pivotally attached at 40 to the arm 6.

A movable weight 41 is adjustable along 120 the scale beam 35 for regulating the pressure upon the arm 6, and the rolls 14 and 15. A like mechanism is provided for adjusting the weight upon the arm 4, by means of the link connection 42. It is obvious that by means of the various adjustments outlined not only can any desired pressure be exerted upon the roll 7 being formed, but also the angle at which the sheet 1 approaches the roller can be changed at will.

Having fully described my invention, what I claim as new and useful, and desire to secure by Letters Patent is:

A winding mechanism of the class described, comprising a number of rotatable rollers mounted upon pivoted levers and grouped about a common center, means for orienting said rollers about a plurality of common centers, means for shifting said common center in a vertical plane, gravitational means for regulating the pressure of said rollers upon a cylindrical roll of material being wound in said winding machine.

In witness whereof I have hereunto affixed
my signature this 1st day of September, 1927.

GEORGE F. ECKSTEIN.
